UNITED STATES PATENT OFFICE.

MICHAEL S. BASSISTY, OF NEW YORK, N. Y.

SEAM-BINDER COVER.

1,356,120.

Specification of Letters Patent.

Patented Oct. 19, 1920.

Application filed October 15, 1919. Serial No. 330,752.

To all whom it may concern:

Be it known that I, MICHAEL S. BASSISTY, a citizen of Russia, residing at New York, county of New York, and State of New York, have invented certain new and useful Improvements in Seam-Binder Covers, of which the following is a specification.

This invention has as its object the provision of a receptacle for holding binding material upon the surface of a sewing machine table, in proximity to the needle and sewing attachment.

A further object is to provide a holder adapted to contain one or two rolls of the binding material, the same being fed outward through openings having rolled or beaded edges preventing damage to the tape or binding material.

These objects are attained by the novel construction and combination of parts hereinafter described, and shown in the accompanying drawings, forming a material part of this disclosure, and in which:—

Figure 1 is a top plan view showing a holder made in accordance with the invention, and indicating its application.

Fig. 2 is a side elevational view of the same.

Fig. 3 is an enlarged top plan view of the holder in detail.

Fig. 4 is a side elevational view thereof.

Fig. 5 is a transverse sectional view taken on line 5—5 of Fig. 3.

Fig. 6 is a fragmentary transverse sectional view taken on line 6—6 of Fig. 4.

Fig. 7 is a fragmentary front view showing the connecting means between the several containers.

Fig. 8 is a fragmentary vertical sectional view taken on line 8—8 of Fig. 3, and,

Fig. 9 is a side elevational view of a single binding receptacle.

Referring to the drawings in detail, the numeral 10 indicates a seam binding attachment for a sewing machine to which it is connected by the slotted bracket 11, allowing adjustment due to the clamp screw 12.

Resting upon the top of the sewing machine table, is the base 15 of the device and formed with the base is a tubular thimble 16, having a conical upper end 17 and adapted to be disposed over a pin or plug set in the table upon which the thimble is readily rotatable.

An annular beading 18 is formed with the base element 15, the same having an

upwardly turned reverse curve 19, and downwardly flanged periphery 20. Resting upon the base is a plate 21, on which the roll of tape or binding material may be disposed.

The interior edge surrounding the center opening in the flange is downturned so as to present no rough or sharp edges to abrade or damage the material.

Disposed in intimate contact with the beading 19, is an outwardly turned curved flange 23, formed with the casing elements 24, acting as a side wall for the container, the upper edge of the wall 24 being beaded outwardly as at 25, and thence formed into a raised cover portion 26, upon which may be disposed another plate 28, in all respects similar to the plate 21, and having a central opening passing over the thimble 16. The downturned peripheral edges 29 of the cover plate 26 are suited to engage with the hook-like lower edges 30 of a second casing 31, having an upper beaded corner 32, from which extends the cover plate 33, terminating in an interior downturned beading 34, adapted to make contact and be guided by the thimble 16, and containing a circular plate 38.

Formed at intervals in the plate 26 and top or cover 33 are radial elongated indentations 35, acting as reinforcements or strengthening elements so as to form a substantially rigid structure.

On opposite sides of the beaded elements 23, 26 and 32 are cut outs 36, 37 and 38, the same being in registration and adapted to lock the several plates in proper relation preventing them from turning.

Formed through the cylindrical walls 24, 38 and 40, respectively in the upper and lower casing, are openings 41 and 42, the material adjacent to the openings being folded tightly as at 43 and 44, thereby presenting rounded surfaces against the tape or binding adapted to contact, as it is unrolled from the interior of the casing in its passage to the sewing machine.

From the foregoing it will be seen that a neat and practical device for containing tape, and binding disposed in a rolled form, through which the thimble 16 is adapted to extend, for guiding and supporting the same and that as the extended ends of the material are withdrawn they are prevented from becoming abraded or otherwise injured in passage to the needle.

Having thus described my invention what I claim as new and desire to secure by Letters Patent, is:—

1. In a device of the class described, the combination with a base having a central hollow thimble formed therewith, a cover disposed over said base, said cover having extending angular flanges engaged with the periphery of said base, a disk disposed on said base adapted to receive a roll of binding material, and means for maintaining said cover in proper relation in said base, the side walls of said cover containing openings having reentrantly turned edges whereby the binding is prevented from becoming damaged.
2. In a device of the class described, the combination with a cylindrical casing having a base, a cover and a horizontal partition therein, means formed with said base extending through said cover and partition, means for holding said cover and partition in alinement with said base, beadings formed with a periphery of said base and cover, a plurality of longitudinally extending radial depressions formed in said base and cover, adapted to act as reinforcements, and means permitting the egress of tape in said casing without damage to the same.
3. In a device of the class described, the combination with a cylindrical casing com-

prising a base and cover, a second casing disposed thereover, a tubular sleeve formed with said base and extending through said cover and said second casing, said base being adapted to be attached to a pin upon which it may be rotated, beadings formed at the peripheral edges of said base and cover, reinforcing devices formed with said cover and base, and means permitting the passage of material from compartments in said casing without damage to the same.

4. In a device of the class described, the combination with a base plate, a hollow standard formed therewith, said standard being adapted to act as a pivot by which said base may be positioned, a hollow cylindrical casing arranged over the base, a second casing arranged over the first named casing, said second casing being guided by said plate, reinforcing means integrally formed with said casing, means for preventing the respective rotation of said casing, and base and passages formed in the peripheral walls of said casing having their edges reentrantly turned providing curved surfaces adapted to contact with the material as it is withdrawn upon the casing.

In testimony whereof I have affixed my signature.

MICHAEL S. BASSITY.
